UNITED STATES PATENT OFFICE.

JAMES ATKINS, OF PHILADELPHIA, PENNSYLVANIA.

SWITCH-LOCK.

1,232,477.

Specification of Letters Patent. Patented July 10, 1917.

Application filed June 21, 1916. Serial No. 104,873.

To all whom it may concern:

Be it known that I, JAMES ATKINS, a subject of the King of Great Britain, residing at Philadelphia, in the county of Philadelphia and State of Pennsylvania, have invented certain new and useful Improvements in Switch-Locks, of which the following is a specification.

My invention consists of an improved switch lock, and is particularly serviceable for use on automobiles, since it will prevent any one other than a person who is authorized to do so, from running or stealing the car.

15 One object of my invention is to provide a combination switch lock which may only be closed after the proper combination has been secured or set.

Another object is to so construct a switch lock of the above described type that it can be quickly and easily operated by a person who knows the proper combination, but is practically inoperative to any one who does not know the combination.

25 A further object is to so make my invention that it will be effective, durable, and can be manufactured at a reasonably low cost.

Another object of my invention is to so 30 construct my improved switch lock that the combination may be quickly changed.

These objects, and other advantageous ends which will be described hereinafter, I attain in the following manner, reference 35 being had to the accompanying drawings in which

Figure 1 is a top plan view of my invention.

Fig. 2 is a sectional elevation taken on the 40 line *a—a* of Fig. 1.

Figs. 3, 4, and 5, are transverse sections taken respectively on the lines *b—b*, *c—c*, and *d—d* of Fig. 2.

A main casing 1, consists of two cup-shaped ends 2 and 3, and two intermediate cylindrical sections 4 and 5. These intermediate sections 4 and 5 are spaced from each other, and from the end sections 2 and 3 to provide room for rotatable rings 6, 7, 50 and 8, which have disks 9, 10, and 11 secured thereto by means of pin-and-hole connection.

Each of the disks 9, 10, and 11 have holes 12 spaced in annular formation adjacent 55 their peripheries, and into these holes project pins 13 which, as illustrated, are ar-

ranged diametrically opposite on inwardly projecting flanges 14 on each of the rings 6, 7, and 8.

From this construction it will be understood that a rotation of any of the rings 6, 7, and 8, will effect a corresponding rotation to its respective disk. Each disk has a radially extending slot 15 and a hole 16.

A central longitudinally extending tube 65 17 is secured to the end section 3 by means of a spider 18. This tube is slotted throughout a portion of its length as at 19, and extends through the holes 16 in the disks 9, 10, and 11.

70 A plunger 20 is designed to slide longitudinally within the tube 17 and has three pins 21 which are in line and under certain conditions are designed to respectively pass through the slots 15 of said disks when 75 the said slots 15 are all brought into alignment.

The inner end 23 of the plunger 20 is recessed at 24, and is designed to engage and form an electric connection between two 80 contacting fingers 25 and 26. These contacting fingers are spaced apart, and form elements which complete an electric circuit, as for example, to the engine or other movable part of the automobile.

85 The plunger 20 is preferably made of metal which is a good conductor of electricity.

It will thus be understood that when the parts are in the position shown in Fig. 2, 90 the contacting fingers 25 and 26 being spaced apart, will not provide a circuit for the electricity, however, if the plunger 20 is moved into contact with both of these contacting fingers 25 and 26, the circuit will be 95 completed.

As shown in Fig. 2, the slots 15 are in the proper alignment, so that when the plunger 20 is pushed inwardly, the pins 21 will pass through the respective slots 15, 100 this motion being sufficient to permit the plunger to engage said electric contacts 25 and 26 to complete the circuit.

The section 2 has an inwardly projecting sleeve 27 which is screw-threaded at 28 to 105 receive the threaded end of the tube 17, and is also provided with a transversely extending slot 29 into which the adjacent pin 21 projects when the plunger is in the position shown in Fig. 2, so that when the plunger 110 is in this position, said latter pin will act as a stop to prevent the section 2 from being

unscrewed or removed. However, if the plunger is pushed as above described, said pin will pass out of the slot 29 and if desired, the section 2 may then be unscrewed from the tube and the several parts may be readily detached.

Each ring 6, 7, and 8, is provided with a series of lines which, in the present instance, is indicated by numerals, and a knife or plate 30 may be mounted on any suitable support so as to project transversely of the ring 6, 7, and 8, as clearly shown in Figs. 1 and 2.

As shown in the several views of drawings, the plunger may be pushed or pulled when all of the zero marks are in line with the edge "x" of the plate 30. However, this combination may be changed by separating the disks from their respective rings and changing the relation between the pins and the holes.

In order to lock the plunger in the position shown in Fig. 2, which is the inoperative position, it is merely necessary to turn one or more of the rings 6, 7, and 8, and unless a person is familiar with the combination, it is practically impossible to secure the proper combination.

I have illustrated three pins 21, and three rings and disks, however, it will be understood that any number of rings, disks, and pins may be employed, the greater the number the more difficult it will be to secure the proper combination by any person who does not know said combination.

My invention may be conveniently placed within the dash board or foot board of an automobile, in which case the plate 30 may be secured to said dash board, and the section 3 may be inserted within said dash board, only the rings 6, 7, and 8, the end section 2, and handle of the plunger being exposed.

The handle 31 of the plunger is screwed or otherwise detachably secured to the end thereof, and if it is desired to take the elements apart, this handle may be first removed after which the end 2 may be unscrewed as hereinbefore stated.

It will be understood that the contacting members 25 and 26 are insulated from the section 3 by means of insulation as shown at 32, however, this section may, if desired, be made of an insulating material in which case it will be unnecessary to furnish further insulation.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. The combination of a casing, a support within said casing, a member slidable within said support, selective rings having portions outside of said casing, disks within said casing and having slots therein, pins on said member, means for detachably connecting said disks to the rings, said disks being moved by said rings to move their slots into and out of alinement with said pins, said member being movable within said casing when the slots and pins are in alinement, means outside of said casing for determining the relative position between the slots and the pins, said casing having a removable cup-shaped end section screwed directly on said support, said end section having a portion projecting within the casing and provided with a slot extending from its innermost edge toward the end of and being formed entirely within said latter section, one of said pins being movable into engagement with said slot when the member is moved into a pre-determined outward position to thereby lock the end section to the support, substantially as described.

2. The combination of a casing, a support within said casing, a member slidable within said support, selective rings having portions outside of said casing, disks within said casing and having slots therein, pins on said member, means for detachably connecting said disks to the rings, said disks being moved by said rings to move their slots into and out of alinement with said pins, said member being movable within said casing when the slots and pins are in alinement, means outside of said casing for determining the relative position between the slots and the pins, said casing having a removable end section screwed on said support, said end section having a sleeve projecting entirely within the casing and through which said first member slides, said sleeve having a slot extending from its inner end longitudinally of said sleeve, one of said pins being movable into engagement with the slot in said sleeve when the member is slid into a pre-determined outward position to lock said latter end section to the support, substantially as described.

3. The combination of a casing having cup-shaped end sections and intermediate cylindrical sections, rings having portions located outside of said cylindrical sections and bridging the space therebetween and between the cylindrical sections and the end sections, said rings having inwardly projecting flanges, disks detachably connected to and held between said inwardly projecting flanges and one of said end sections, said disks having centrally extending holes and radially extending slots, a tubular support

fixed within said casing and having a longitudinally extending slot, a plunger slideable within said tubular support, pins on said plunger extending through said slot in the support, said disks being moved by said rings to move their slots into and out of alinement with said pins, said member being movable within said casing when the slots and pins are in alinement, means outside of said casing for determining the relative position between the slots and the pins, means for positively connecting said tubular support to one end section, means for detachably connecting said tubular support to the opposite end section, and means for locking said latter section to the support when the plunger is in a pre-determined position, substantially as described.

4. The combination of a casing having cup-shaped end sections and intermediate cylindrical sections, rings having portions located outside of said cylindrical sections and bridging the space therebetween and between the cylindrical sections and the end sections, said rings having inwardly projecting flanges, disks detachably connected to and held between said inwardly projecting flanges and one of said end sections, said disks having centrally extending holes and radially extending slots, a tubular support

fixed within said casing and having a longitudinally extending slot, a plunger slideable within said tubular support, pins on said plunger extending through said slot in the support, said disks being moved by said rings to move their slots into and out of alinement with said pins, said member being movable within said casing when the slots and pins are in alinement, means outside of said casing for determining the relative position between the slots and the pins, means for positively connecting said tubular support to one end section, said tubular support having a threaded end, the other of said end sections having an inwardly projecting internally threaded sleeve designed to fit the threaded end of the support, said sleeve having a slot at its inner end, one of said pins being movable into engagement with said latter slot when the plunger is slid into a pre-determined outward position to thereby lock said latter end section to the support, substantially as described.

In testimony whereof I have signed my name to this specification in the presence of two subscribing witnesses.

JAMES ATKINS.
